UNITED STATES PATENT OFFICE.

CARL F. ANDERSON, OF BROOKFIELD, AND LESTER W. KNAPP, OF BERWYN, ILLINOIS,
ASSIGNORS, BY MESNE ASSIGNMENTS, TO CONLON CORPORATION, OF CICERO, ILLINOIS,
A CORPORATION OF ILLINOIS.

WOODWORKING MACHINE.

Original application filed August 27, 1920, Serial No. 406,388. Divided and this application filed August 27, 1920. Serial No. 406,389.

To all whom it may concern:

Be it known that we, CARL F. ANDERSON and LESTER W. KNAPP, both citizens of the United States, residing at Brookfield, in the county of Cook and State of Illinois, and Berwyn, in the county of Cook and State of Illinois, respectively, have invented a certain new and useful Improvement in Woodworking Machines, of which the following 10 is a full, clear, concise, and exact description, reference being had to the accompanying drawings, forming a part of this specification.

Our invention relates to wood working machines, being a division of our co-pending application, Serial No. 406,388, filed August 27, 1920, covering improvements in wood working machines, in which a blank is formed into a finished head, employed in 20 the construction of rotating cylinders for washing machines.

Although our invention is adapted to perform an operation particularly upon a washing machine cylinder head, we do not 25 intend to be limited thereto, as it is apparent and obvious that this operation may be extended to and embodied in machines for making other articles of analogous form, or even articles of dissimilar form, but which 30 require the performance of substantially the same operation in whole or in part.

Generally in the construction of rotary cylinders, two head members are employed, and to these heads the slats are secured. 35 The perimeter of the head members are usually circular or elliptical in configuration, which require that the surface of the slat, laid upon the perimeter of the head, should be concave. This prevents splitting 40 or warping of the slat. The slats are so spaced upon the heads that a spaced opening is preferably maintained between adjacent slats, which provides for agitating of the washing fluid, augmented by the 45 perforations in the slats. In the assembly of rotary cylinders, the spacing of the slats on the heads, so that a proper spaced opening between the slats is secured, presents a practical difficulty. Even, when the cylinder head is formed polygonal, as disclosed 50 in our above mentioned co-pending application, and an individual perimetrical face

is provided for each slat, the aligning and proper spacing of the slats became tedious.

It is the primary aim of our invention to 55 overcome the above difficulties in the mounting of slats upon the cylinder heads by providing a mechanism which will rotate and retain the heads periodically to present a certain portion of the perimeter to a boring mechanism, thereby causing nail or screw holes to be drilled in the perimeter of the head, which at the same time are properly spaced. Hence, much tedious labor 60 in the assembly is eliminated.

Another aim of our invention is to provide a boring mechanism wherein the working elements can be quickly and easily adjusted for the purpose of readily adapting 65 the mechanism to different size heads, or heads of different characteristics.

The construction and operation of a preferred embodiment of our invention will be more readily understood from the following 70 detail description taken in connection with the accompanying drawings, in which:

Figure 1 is a front elevational view of a machine embodying our invention;

Figure 2 is a transverse sectional view taken on line 2—2 of Figure 1, illustrating 75 the part of a machine comprising our invention;

Figure 3 is a fragmentary sectional view illustrating the means employed for controlling the various positions of the head 80 during the boring operation;

Figure 4 is a fragmentary sectional view of the same mechanism taken on a different plane, illustrating the releasing device employed;

Figure 5 is a detail fragmentary section of the spring connection of the connecting rod of the reciprocating boring mechanism;

Figure 6 is a detail side elevational view of the boring mechanism;

Figure 7 is a detail top plan view of the same;

Figure 8 is a sectional view taken on line 8—8 of Figure 6;

Figure 9 is a front elevational view of 100 the cylinder head; and

Figure 10 is a side elevational view of the same, illustrating the nail or screw holes employed for securing the slats to the head.

By referring to Figure 1 it will be seen that we have shown our invention embodied in a machine in which the cylinder heads are shaped polygonal and nail openings bored therein, by means of a cutter knife controlled by a feeling cam and roller, and a boring mechanism which performs the boring operation. The boring operation is performed during the cutting operation and forms the nail or screw holes in the lateral faces of the heads to receive the carrying brackets of the cylinders. We have deemed it not essential to further show this mechanism as it has been fully described and claimed in our co-pending application.

In order to clarify matters a brief description, so far as the showing permits, will be given. The head clamp 10 suitably retains the blank 11 under pressure by means of the air chuck 12, which is operated by means of the lever 13 controlling a valve 14 having communication with the supply pipe 15 and air chuck 12 by means of the pipes 16. The air chuck functions to provide translational movement to the movable plate 16' of the head clamp 10 so that the blank 11 may be inserted and removed from the clamp 10. The cutter mechanism, not shown, is driven from the main power shaft 17 by means of the pulley 18 and belt 19. This cutter mechanism is advanced toward the projecting perimeter of the blank 11 by means of the lever 20 manually controlled by the operator of the machine. The cutter knife of the cutter mechanism is adapted to travel the perimeter of the blank in a pre-described path, viz., polygonal. This is accomplished by the polygonal shaped cam 21 on the clamp 10 which is adapted to guide the travel of the cutter knife by engaging a feeling roller on the cutter shaft. The boring mechanism which bores the nail holes in the lateral faces of the head comprises the drum or head 25 adapted to laterally advance toward the head clamp. The drum 25 is rotated at a relatively slow speed, while the drills 26 carried thereby are driven at a relatively high speed. The drive for the drills 26 is taken directly from the power shaft 17 by means of the pulley 27, belt 28 and gear pulley 29. The drive for the drum 25 includes the power shaft 17, countershaft 30 and driving shaft 31, these shafts comprising in part a double gear reduction.

The supporting structure for carrying this mechanism comprises the two front uprights or legs 32-32; and the two rear legs 33-33. The front legs are joined together by means of the upper and lower longitudinal timbers 34-34 which are reinforced in the center by the post 35, serving to support the power transmission mechanism and operating parts of the machine. The rear legs 33-33 are also joined together by means of the upper and lower longitudinal timbers

36-36. The front and rear supporting units are joined together at each end by the upper and lower cross timbers 37 and 38 respectively and the intermediate bracing timbers 39.

The mechanism embodying our present invention will now be described. By reference to Figure 10, it will be seen that the perimeter of the finished head 40 is provided with the holes 41 for the reception of 75 the nails or screws 41 which secure the slats 42 to the head. After shaping the perimeter of the head 40 polygonal and boring the lateral nail holes 43 and mortise openings 44 while in the head clamp 10, the air 80 chuck control lever 13 is manipulated to open the head clamp 10 and thereby release the head 40. The head is then removed and placed upon the plate 45, which is carried by the vertically disposed shaft 46, the 85 shaft 46 being carried by the bearing 47 mounted on the upper timber 34 and the bearing 48 mounted on the lower timber 34 of the supporting frame. The plate 45 is provided with a set screw 49 which permits of adjustment on the shaft 46, should a head 90 of different thickness be used. The upper cross members 37 of the frame support two laterally extending cross timbers 50 and 50' upon which is carried the bed 52.

As shown in Figures 6 and 7, the bed member 52 is provided with a plurality of side lugs 51, which seat upon the cross timbers 50 and 50', and which are secured thereto by means of the bolts 54. As shown in Figure 8, a plate 55, having a dovetailed seat, is provided in the upper portion of the bed 52 and is adapted to reciprocate therein by means of a mechanism which will be hereinafter described. The gib 56 provides for an adjustment of this plate 55 in its bearings by means of the screws 57. Formed upon the plate 55, such as by casting, integral, welding, or otherwise, is the 105 boring box 58 in which are disposed the drills 59. The box 58 comprises the member 59', which is rigidly or otherwise secured to the plate 55, the removable intermediate member 60 and the removable top member 61. The drills 59 are removably secured to the 110 stocks 62 by means of the set screws 63'. The members 59' and 60 are provided with bearings for the shafts 63, which have semi-circular bearing sleeves 64' therein. At the other or opposite end of the bit shaft 63 the 115 gears 64 are disposed, which have meshing engagement with the driving gear 65. This gear 65 is carried by a shaft 66, also disposed within the housing 58, and is provided with a similar bearing between the intermediate 120 member 60 and top member 61. The opposite end projects through the housing 58, being reduced and having a nut 67 threading thereon to prevent lateral displacement. A driving pulley 68, mounted on the reduced 125

gear end of the shaft 66, is driven by any suitable source of power (not shown) through the belt 69. Adjustment of the bearings for the bit shafts 63 is secured through the screws 70, which secure the intermediate members 60 to their rigid member 59'. Likewise, adjustment of the driving shaft 66 is secured by the screws 71 which secures the member 61 to the intermediate member 60.

The bed 52 is of such length that the guideway formed therein for reception of the reciprocating plate 55 allows for movement sufficient to permit the plate 55 to advance the drill bits 59 toward the head 40 lying on the retaining plate 45 to perform a drilling operation in the perimeter. Of course, it is to be understood that this drilling or boring operation does not necessarily have to be performed in the perimeter of the head 40, or does the head necessarily have to be of a disk formation, as the essence of this invention lies in the general arrangement of the mechanism for performing this operation.

As clearly shown in Figure 2 the cross timbers 50 and 50' are cut away at their upper portions as indicated at 71, so as to permit clearance for the connecting rod 72. The connecting rod 72 is disposed in the lower recess portion of the bed 52, and has connection at one end with the plate 55 and at the other end an eccentric connection with the disk 75 mounted on the upper end of the shaft 76. A similar disk 77 is also carried on the shaft 76 directly below the disk 75, and upon each of these disks are formed the cam 78. The shaft 76 is supported upon the cross timbers 37 and 38 by means of the bearings 79. At the lower end of this shaft a third disk or plate 80 is carried, which also has a cam or projection 81 thereon. The counter shaft 30 drives the shaft 76 through the pulley 82 and belt 83, having a slip drive with the pulley 84.

The cam 78 is periodically engaged by a lever 85 fulcrumed to the member 39 at 86. The lower end of the lever 85 carries a bar 87 bolted thereto which has secured at the free end thereof the roller 88 engaged by the cam 81. The bar 87 retains one end of the spring 89 while the other end is held by a rod 90 rigidly secured in the supporting leg 33. The spring 89 functions to keep the upper end of the lever 85 out of engagement with the cams 78 of the plates 75 and 77 and the roller 88 on the lower end of the lever in engagement with the cam 81 of the plate 80. Directly above the bearing 47 a plate 91, having a plurality of peripheral slots 92 therein, is carried on the shaft 46. Referring to Fig. 3, there is a slot for each face of the polygonal head 40, or in other words, for each slat of the rotary cylinder, except that portion of the plate designated 93.

This portion 93 is equivalent to the space occupied on the cylinder head by the cover of the washing machine cylinder. While it is necessary to form the faces 95 on this portion of the head, it is not necessary to drill the nail holes 41, as the cover of the cylinder is removable and hence the cover slats are not secured to the head. Each slot 92 is adapted to be engaged periodically by the lever 85, so that the reciprocating plate 55 may be allowed to advance toward the head on the plate 45, and consequently permit the bits 59 to bore the holes 41 in the faces 95. The shaft 46 carrying the plate 45 has a driving connection similar to that for the shaft 76, that is, a belt 96 is trained over the pulley 82 and has a slip connection with the pulley 97.

The operation of this mechanism will be evident from the following: The spring 89 constantly tends to keep the lever 85 in engagement with the slots 92. As the shaft 76 rotates in the direction of the arrow, as shown in Figures 3 and 4, the cam 81 engages the roller 88 and consequently cams the lower end of the lever 85 outwardly against the tension of the spring 89. The lever 85 is then thrown out of engagement with the slot 92 and into engagement with the projections 78 on the plates 75 and 77, and thus the shaft 76 is locked against further rotation. The cam 81 is so timed in its performance that the tip or the peak of its dwell just clears the roller 88 as the shaft 76 is locked against rotation. The slip drive between the belt 96 and pulley 97 then picks up and the shaft 46 rotates in the direction of the arrow, shown in Figure 3, to the succeeding slot. The inner edge of the lever 85 bearing upon the periphery of the plate 91 immediately slips into engagement with this slot by means of the spring 89. The shaft 76 then rotates again until the cam 81 engages the roller 88 on its next revolution. During this period of rotation, the eccentric action of the connecting rod 72 and disk 75 bring the boring bits 59 into boring operation with the adjacent peripheral face 95.

This operation is continually repeated until the portion 93 of the perimeter of the plate 91 advances into engagement with the lever 85, whence the shaft 76 is held against rotation for a greater period of time. The shaft 46 rotates and carries the faces 95 of the head 40, on which the slats lie, past the boring box 58 without permitting the boring operation to be performed.

As the boring box 58 approaches the head 40 on the plate 45 its movement is unimpeded until the bits 59 engage the face 95, when the movement is retarded slightly, due to the resistance the bits 59 offer at the initial engagement. The shaft 76 continues to rotate, which consequently carries the con-

necting rod 72 around its path of movement. Due to the elliptical shaped head, which I also contemplate working on, and which provides faces 95 having unequal radii, the stroke of the boring mechanism should preferably vary in length. To accomplish this a resilient connection is interposed in the connecting rod, the details of which connection are shown in Figure 5. A sleeve-like spring housing 99 is interposed in the connecting rod 72, this housing having a reduced end 100 connected with the reciprocating plate 55 by means of the bolt 73 threading into the plate 55. The other portion of the connecting rod 102 is guided for motion in the spring housing 99 by the guide nut 101 which runs into and closes off the outer end of the housing 99. The end of the connecting rod section 102 is provided with a collar 103 and confined between this collar and guide nut 101 is a compression spring 104. As the shaft 76 rotates, the portion 102 of the connecting rod 72 follows in an eccentric path about the disk 75, and when the drills 59 initially engages the perimeter of the head 40, the head 103 at the opposite end compresses the spring 104 till the tension is sufficient to overcome the resistance of the drills 59, which is offered at its initial operation. So long as the drive is positive, as it is in this case, such a resilient connection obviates any undue strain upon the drill 59 or other operating elements.

In an elliptical head, the faces having the lesser radii will require boring box 58 to advance the drills a greater distance in order that the holes drilled will be of the desired depth; and vice versa. In the latter instance where the faces presented have the greater radius, the shoulders of stocks 62 abut the periphery of head 40 after bits 59 have cut a maximum distance in the head. The remaining part of the stroke made by the eccentric connection is taken up by the spring 104. Thus a variation in the length of the stroke is obtained.

While we have described our invention in detail in this particular embodiment, it is clearly apparent that the features of our invention may be incorporated in various and many ways in machines performing analogous and also similar functions; that the timing element employed for permitting the head or product of the machine to revolve and present a new portion on the perimeter, or any other part thereof, while the boring mechanism is substantially held from movement, may be altered considerably and yet be within the essence of our invention; and hence, we do not intend to limit ourselves to the particular construction and arrangement shown.

We claim:

1. In combination, a shaft, means on said shaft for retaining a blank, driving means

for said shaft, a locking element on said shaft for preventing rotation thereof during certain periods of operation, an arm for engaging said locking element, said arm having a roller at the lower end thereof, a second shaft, means for driving said second shaft, boring mechanism, means for advancing the latter operated by said second shaft, a second locking element on said second shaft, and a cam on said second shaft engaging said roller for moving said arm into engagement with said second locking element whereby advancing movement of said boring mechanism is prevented.

2. In combination, a work moving shaft, mechanism for performing an operation on a piece of work moved by said shaft, a shaft for moving said mechanism into and out of engagement with said work, an escapement permitting one only of said shafts to rotate, a slip-friction drive for each shaft, and cam means on the work moving shaft to predetermine a non-uniform sequence of displacements each less than a complete revolution.

3. In combination, a work moving shaft, mechanism for performing an operation on a piece of work moved by said shaft, a shaft for moving said mechanism into and out of engagement with said work, a slip-friction drive for each shaft, and an escapement permitting only one of said shafts to rotate and stopping each shaft before the other shaft can start.

4. In combination, means for shifting a piece of work, mechanism for performing an operation on said work, means for moving said mechanism into and out of operative engagement with said work, and means controlled by said work shifting means for preventing operation of said mechanism moving means during movements of said work through varying displacements between successive operations of said mechanism.

5. In combination, a work support, mechanism for operating on the work on said support, means for shifting said support, an escapement permitting actuation of only one of said shifting means and operating mechanism at a time, said escapement normally tending to start said operating means, and a pattern operated by said work support to prevent movement of the escapement until after a predetermined movement of said support.

6. In combination, a rotatable work carrying shaft, an index plate on said shaft, said index plate having irregularities of contour irregularly spaced, and start and stop mechanism controlled by registry with said irregularities of contour for periodically performing an operation on said work.

7. In combination, a rotatable work carrying shaft, an index plate on said shaft, said index plate having irregularities of

contour, and start and stop mechanism controlled by registry with said irregularities of contour for periodically performing an operation on said work.

5 8. In combination, a rotatable work support, mechanism for performing an operation on a piece of work on said support, connections for intermittently and alternately shifting said support through a constant 10 predetermined angle and then performing

an operation thereon, and which terminate the series of equal angular displacements before said work support has made a complete revolution and complete the revolution without further operations.

In witness whereof we hereunto subscribe our names this 17th day of June, 1920.

CARL F. ANDERSON.
LESTER W. KNAPP.
